UNITED STATES PATENT OFFICE.

CURT KÖDDERITZSCH, OF DORTMUND, GERMANY.

DEVICE FOR AUTOMATICALLY LOWERING THE TROLLEY-POLE OF ELECTRICALLY-DRIVEN VEHICLES.

1,127,453.

Specification of Letters Patent.

Patented Feb. 9, 1915.

Application filed October 11, 1913. Serial No. 794,612.

To all whom it may concern:

Be it known that I, CURT KÖDDERITZSCH, a citizen of the German Empire, residing at Dortmund, Germany, have invented a new and useful Device for Automatically Lowering the Trolley-Poles of Electrically-Driven Vehicles, of which the following is a specification.

The object of the present invention is to provide means for automatically lowering the trolley pole of electrically driven vehicles, whenever it has jumped the overhead wire, so that the pole is prevented from hitting the suspension members of said overhead wire.

According to the present invention the trolley pole is lowered by the action of a spring of suitable strength which, as long as the pole travels along the wire, is kept under tension by an arresting device, but is automatically released after the pole jumps the wire, whereupon it will rotate the drum for the cable attached to the pole in such a manner that the pole is hauled down. With my novel construction, the members for releasing said spring under tension are so arranged relatively to the cable drum that they are axially displaced when the spring is released and the drum is rotated, while they are automatically re-set for the next operation by exercising a pull on the pole cable wound upon the drum.

In the accompanying drawing: Figure 1 is an axial section of a trolley pole-lowering device embodying my invention, Fig. 1^a a perspective view of the spring barrel and adjoining parts, Fig. 2 a cross section on line E—F, Fig. 1, the parts being shown in the position which they occupy immediately before the release of the spring barrel, Fig. 3 a similar section showing the parts in different position, Fig. 4 an axial section through a modification of my trolley pole-lowering device, Fig. 4^a a perspective view of the cable drum shown in Fig. 4, Fig. 5 a cross section the upper half of which is taken on line A—B, Fig. 4 while the lower half is taken on line C—D, Fig. 4, Figs. 6 and 7 are similar sections showing the parts in different positions, Fig. 8 is a sectional side view of the safety device for locking the apparatus while the same is carried from one car end to the other end, and Fig. 9 a left hand face view thereof.

With the construction embodied in Figs. 55 to 3, the letter *a* designates a shaft which is provided with a thread of suitable pitch and carries a winding drum *b* and a flanged locking disk *c*. To drum *b* is attached one end of the pole cable, while a spring *g* interposed between shaft *a* and drum *b*, tends to so rotate the drum as to wind the cable thereon. As long as the trolley pole is forced down by the overhead wire, the spring *g* will thus turn the drum *b* in a direction opposite to that of a clock hand, when seen from the left (Fig. 1), so that the drum is moved toward the right owing to its engagement with the thread of shaft *a*. When the cable unwinds, for instance 70 in case the trolley wheel jumps the wire, it will turn the drum in the opposite direction thereby moving the drum toward disk *c*. On the opposed faces of drum *b* and disk *c* are provided lugs *d* and *e* respectively. 75 The height of these lugs and the pitch of the thread should be so selected that in the position shown in Fig. 1, the lugs are free to pass in front of each other, while they will abut against each other, after drum *b* 80 has performed one complete rotation caused by a pull on the pole cable. Disk *c* is rotated by a strong trolley pole hauling spring *f*, when the latter has been released, in the same direction as the drum *b* is turned by 85 the weaker spring *g*, thus in Figs. 2 and 3 contrary to the movement of a clockhand.

By means of a pawl or detent *h* pivoted to the casing *i* of the device and engaging a groove or recess *t* of disk *c*, the latter is prevented from rotating, until this pawl *h* has been lifted by the drum *b*. This lifting of pawl *h* is effected by means of a tappet *k* fulcrumed to drum *b* and adapted to engage a stud *z* of the pawl slightly before lug *d* 95 abuts against lug *e*. Casing *i* is further provided with a fixed pin *z* adapted to be engaged by the pawl *h* thereby preventing the latter from being swung inward to a greater extent than corresponds to the inward movement of said pawl when engaging the most depressed portion of spiral groove *t*. After the pawl *h* has thus been released by tappet *k*, the comparatively strong spring *f* 100 is free to rotate disk *c* in a direction opposite to that of a clock hand when seen from the left (Fig. 1). As soon as during this rotation of disk *c*, its lug *e* abuts against the

lug d of drum b , the latter will participate in the rotation of disk c , while at the same time, the disk and drum travel toward the right (Fig. 1), owing to the thread provided 5 on shaft a , which thread is engaged by the disk and drum as clearly illustrated in Fig. 1. In this way the cable is wound upon drum b , thus hauling down the trolley pole. For preventing the pawl h from reengaging 10 recess t after the first revolution of the disk c has been performed, the width of recess t should be slightly less than the pitch of the thread, so that after one revolution of the disk, the pawl h can no longer enter said 15 recess.

For allowing the springs f and g to participate in the movement of the parts b , c toward the right during the operation described, they are secured to sleeves m and n , 20 respectively, which are prevented by a key o from revolving, said key sliding in a groove p in the shaft.

When the disk c is to be returned with its spring under tension to its initial position, it is sufficient to pull out the cable. 25 The lug d will then drive lug e and disk c and drum b will revolve clockwise. In this way the drum b and the disk c will again travel to the left, Fig. 1, until the pawl h 30 reengages recess t .

As above described, pawl h rests on pin α whenever disk c has been moved toward the right (Fig. 1) and away from said pawl for the purpose of hauling down the cable. In 35 order to prevent the subsequently returning disk c from abutting laterally against the pawl, whereby its further return movement would be checked, the flange of disk c is rounded off or made coniform as clearly 40 illustrated in Fig. 1. The pawl h will thus climb the conical flange until it finally drops into recess t . During this movement the lugs d and e bear against each other and the tappet k is located back of the releasing 45 lug z of the pawl h . When the cable is released the spring g will revolve the drum with lug d and tappet k in a direction opposite to that of a clock hand until the parts occupy the position shown in Fig. 1. During 50 this movement of the drum, pawl h retains its locking position as tappet k is able to yield toward the right (Fig. 3) to be subsequently righted by a comparatively weak spring q .

With the modification shown in Figs. 55 4-7, shaft a is journaled in the rear wall w of the casing, which is adapted to be secured to the car. To this shaft there is secured one end of a powerful return spring c^1 the 60 other end of which is attached to the back wall w , this spring tending to turn the shaft in such a direction as to wind up the cable. To the shaft a is also rigidly coupled a disk d^1 provided with a notch d^2 which is adapted 65 to be engaged by the retaining pawl e^1 in

such a manner, that the shaft a is prevented from being turned by spring c^1 the pawl e^1 being carried by a spring e^2 riveted or otherwise secured to casing g^1 . On the shaft a is further rotatably fitted the cable drum 70 f^1 . To this drum is secured one end of a spring g^1 , the other end of which is secured to shaft a and tends to turn the drum in the same direction, as spring c^1 , the spring g^1 however being weaker than spring c^1 and 75 serving only to keep the cable taut, whereas the spring c^1 is under so high a tension, that it is able to haul down the trolley pole. Between the disk d^1 and the drum f^1 , a releasing disk h^1 is fitted. This disk is connected on the one hand to shaft a by means 80 of its screw thread and on the other hand to drum f^1 by inwardly extending projections i^1 of said drum, which engage corresponding recesses k^1 of disk h^1 . In this 85 way, a rotation of drum f^1 owing to an unwinding of the cable, will cause disk h^1 to participate in this rotation, while the engagement of the disk with the thread of shaft a causes said disk to move toward 90 disk d^1 .

To disk h^1 is pivoted a catch or tappet l , which is forced, by means of a spring m^1 , against an abutment n^1 . When disk h^1 has sufficiently approached disk d^1 owing to the 95 trolley jumping the wire and to the resulting unwinding of the cable, the catch l engages (from left to right, Fig. 5) under the shoulder o^1 of the pawl e^1 and lifts the latter until it clears notch d^2 . On the disks h^1 , d^1 100 are respectively provided the lugs p^2 and p^1 . In consequence of the pawl being lifted, spring c^1 is released and shaft a is revolved, which movement is transmitted to drum f^1 through lugs p^1 , p^2 thus winding the cable 105 on said drum. In order to prevent a reengagement of pawl e^1 with notch d^2 after disk d^1 has performed one complete revolution, a second catch l^1 is provided on disk d^1 110 which is forced by spring m^2 against an abutment n^2 . By means of the catch l^1 the pawl e^1 is lifted at the completion of each 115 revolution of disk d^1 thereby preventing an engagement of pawl e^1 and notch d^2 . Fig. 6 shows the position of the parts after disk d^1 has completed one revolution. The device is set for the next use by simply pulling out the cable. At each full revolution of drum f^1 the pawl e^1 will engage the notch d^2 of disk d^1 , as the catch l^1 is able to yield and 120 thereby no longer lifts the pawl. After a sufficient number of revolutions, *i. e.* when the disk h^1 abuts against the disk d^1 the cable is released and the disk h^1 recedes in consequence of the drum being turned backward under the action of spring g^1 , the catch l falling over and passing underneath the lug o^1 of the pawl. The device is thus 125 again ready for use.

The whole arrangement is inclosed within 130

a casing q^1 which has a slot through which the cable passes, and in which the shaft a is journaled.

As evident from the drawings the distance 5 between the lugs p^2 and p^1 , and between the catches l and l^1 , and the length of the lug o^1 should be so selected, that the catch l may be righted while the catch l^1 remains tilted.

The safety device shown in Figs. 8 and 9 10 consists of the following parts: The wall w^1 is provided with a socketed lug r , which is adapted to receive a pin s influenced by a spring t^1 that tends to move said pin toward the cable drum. The flange of the latter is 15 provided with notches adapted to be engaged by the pin, thereby preventing a further rotation of the drum, when the entire device is carried from one platform of the car to the other platform at a reversing point of the 20 line. For subsequently releasing the lock after the device has again been fitted to the car, the pin s passes outward through the wall a^1 and is there coupled with a lever u which participates in the movement of said 25 pin. Lever u is provided with a tail u^1 that abuts against the member v of the bayonet joint employed for holding the entire device to the car. During the insertion of member v^1 into member v , lever u is tilted thereby 30 withdrawing pin s from the drum-notches, and thus releasing the drum.

I claim:

1. A device of the character described, comprising a threaded shaft, a cable drum 35 permanently engaging the thread thereof, a disk carried by the shaft and also permanently engaging the thread thereof, a first relatively weak spring influencing the drum, a second relatively strong spring influencing 40 the disk, means for locking the disk against rotation, means having a constrained movement and actuated upon a rotation of the drum in one direction for releasing said disk-locking means, and means actuated 45 upon a release of said disk-locking means for transmitting motion from the disk to the drum in the opposite direction, said last named means being also constituted to rewind the second spring upon a rotation of 50 the drum in the first named direction.

2. A device of the character described comprising a casing, a shaft journaled there-

in and having a threaded portion, a cable drum permanently engaging said threaded shaft-portion and having a lug, a recessed 55 disk also permanently engaging said threaded shaft-portion and having a lug that is adapted to engage the drum-lug, a first relatively weak spring engaging the drum, a second relatively strong spring engaging the 60 disk, a pawl pivoted to the casing and adapted to engage the disk-recess, and means actuated upon a rotation of the drum in one direction for disengaging the pawl from the disk-recess, thereby releasing the disk and 65 causing a subsequent engagement of the disk-lug with the drum-lug for rotating the drum in the opposite direction.

3. A device of the character described, comprising a casing, a shaft journaled therein and having a threaded portion, a cable drum permanently engaging said threaded shaft portion, a first relatively weak spring interposed between said shaft and drum, a locking disk also permanently engaging the 75 threaded shaft portion, a second relatively strong spring interposed between the shaft and disk, means pivoted to the casing for locking the disk, means actuated upon a rotation of the drum in one direction for releasing said disk-locking means, and means actuated upon a release of said disk-locking 80 means for transmitting motion from the disk to the drum in the opposite direction, said last named means being also constituted to 85 rewind the second spring upon a rotation of the drum in the first named direction.

4. A device of the character described comprising a casing, a shaft journaled therein and having a threaded portion, a spring-influenced cable drum engaging said threaded shaft portion, a tappet pivoted to the drum, a spring-influenced recessed disk also mounted on the threaded shaft-portion, a pawl pivoted to the casing and adapted to 90 engage the disk-recess, a stud on the pawl that is adapted to be engaged by the tappet, and coöperable motion transmitting lugs on 95 said drum and disk.

CURT KÖDDERITZSCH.
